Ninja FB151GY FrostVault 50qt Hard Cooler with Dry Zone, Ninja, customer review oldest date Jul. 22, 2024 [online], [site visited May 20, 2025], available from the internet URL: <https://www.amazon.com/Ninja-FB151GY-FrostVault-Integrated-Fridge-Temp/dp/B0CV5NNG3W/> (Year: 2024).*

Primary Examiner — George A Bugg*Assistant Examiner* — Ji Sun Yoon(74) *Attorney, Agent, or Firm* — Mintz, Levin, Cohn, Ferris, Glovsky and Popeo, P.C.(57) **CLAIM**

The ornamental design for a cooler, as shown and described.

DESCRIPTION

FIG. 1 is a front perspective view of a cooler, showing out new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines shown in the figures illustrate portions of the cooler that form no part of the claimed design.
